United States Patent Office

Des. 196,296
Patented Sept. 17, 1963

196,296

AUTOMOBILE

Rudolph Lusti, 618 Orange St., Chula Vista, Calif.

Filed July 2, 1962, Ser. No. 70,748

Term of patent 7 years

(Cl. D14—3)

Fig. 1

Fig. 2

Fig. 3

Fig. 4

Fig. 5

FIGURE 1 is a side elevational view of an automobile showing my new design, both sides being similar;

The dominant features of my design reside in the portions shown in full lines.

I claim:

The ornamental design for an automobile, as shown and described.
